His Attorney.

UNITED STATES PATENT OFFICE

2,492,750

FLUORESCENT LAMP STARTER.

James P. Hunter, Stratford, Conn., assignor to
 General Electric Company, a corporation of
 New York

Application January 18, 1947, Serial No. 722,825

1 Claim. (Cl. 175—320)

1

The present invention relates to apparatus for starting fluorescent lamps, particularly lamps having at least one electron emitting cathode.

Starters for fluorescent lamps as heretofore proposed include a switch, which may be of the glow tube type, for opening the circuit to the electron emitting cathode so that a high voltage is impressed across the lamp from a ballast device to start the arc in the lamp. In other prior arc starters, the starting switch unit includes not only the starting switch, but also a lockout switch by which the starting switch is rendered inoperative after it has made a number of unsuccessful attempts to start the lamp. In some cases the lockout switch is manually reset, but in others it is automatically reset. The lockout switch mechanism usually includes a thermal element such as a bi-metallic strip carrying a contact which cooperates with a fixed contact. If the lamp fails to start, the two contacts are separated by the bi-metallic strip which is heated by locally supplied heat produced by the flow of current through a resistor.

It is an object of my invention to provide an improved automatic reset starter which is inexpensive to manufacture and extremely accurate and reliable in operation.

The above and other objects of my invention will best be understood from the following description taken in connection with the accompanying drawing in which Fig. 1 shows a complete starter in front elevation, with the enclosing can in section; Fig. 2 shows an end elevation of the device shown in Fig. 1; Fig. 3 is a rear elevation of the device shown in Fig. 1; Fig. 4 is a section taken along the line 4—4 in Fig. 1; and Fig. 5 is a schematic element and circuit diagram of the starter according to my invention.

As shown on the drawing, the starting device comprises a suitable enclosing can 1, closed at the bottom by a plate of insulating material 2 in which are mounted connection pins 3 and 4 whereby the device is connected into circuit with the fluorescent lamp 5. Perpendicularly mounted on the base 2 is a support 6 of insulating material. On one side of the support there are mounted a starting glow switch 7, and a capacitor 8. An L-shaped bi-metallic strip 9 is also mounted on the support by means of two rivets 10 and 11 passing through holes in one arm of the L. The other arm of the element 9 is horizontally disposed and is free to bend and to move perpendicularly to the plane of the support 6. For this purpose a part of the upper portion of the support 6 is cut away as shown in Fig. 3. At the free end of the element 9 there is secured a contact element 12, preferably of a precious metal such as silver, which may be in the form of a short piece of wire secured to the bi-metallic element 9 by spot welding. The contact 12 is arranged

2

to cooperate with a similar contact 13 secured to the main bi-metallic thermal member 14 which is mounted on the opposite side of the supporting plate 6 as by rivet 15 and by rivet 20.

5. The bi-metallic element 14 is primarily actuated by heat generated by a low ohmic resistor 16 which may be of the kind described in Patent No. 2,391,680 of Leonard W. Cook, issued December 25, 1945, and assigned to the same assignee 10 as the present application. As described in that patent, the resistor 16 may comprise a low ohmic resistance coil wound on a core of low heat conductivity which is connected to the thermal member by a member having good heat conductivity 15 and which provides a restricted path for the transfer of heat from the core to the thermal member. This thermal conducting member is shown in Fig. 3 at 17.

The thermal element 14 may further be operated by heat produced by a holdout heater 18 which comprises a high ohmic resistance device. According to my invention I provide for direct thermal conduction of the heat produced by the resistor 18 to the thermal element 14 at the rivet 20.

To this end I prefer to make the resistor 18 of carbon or other high resistance heating material with highly thermally conductive metal leads one of which serves as a metallic heat conducting element 19 which is welded or soldered to the element 14 at the rivet 20 or is otherwise secured to the element 14 to provide good thermal conductivity between the resistor 18 and the thermal element 14. This lead 19 is very short which results in high conductive efficiency since little heat is dissipated by air conduction or radiation. As shown in Figures 2, 3 and 4 of the drawing, the lead 19 is not substantially longer than the resistor's diameter. The thermal conducting element 19 simultaneously serves to make an electrical connection between the resistor 18 and the thermal element 14.

The electrical connections of the various elements are shown in Fig. 5 and the operation of the device will be clear therefrom. When the line switch is closed, current will initially flow through the first filament in the fluorescent lamp 5 through the glow switch 7, through the bi-metallic strip 9, the cooperating contacts 12 and 13 which are normally closed, the bi-metallic strip 14, resistor 16, the second filament of the lamp 5, to the other side of the line. After a predetermined period of time, the resistor 16 produces sufficient heat, which is conducted through the conducting member 17 to the bi-metallic strip 14, to cause the strip 14 to deflect contact 13 away from contact 12, thereby opening the starting circuit. Normally, the arc in the lamp 5 will then start under the influence of the high voltage produced by the ballast in the circuit. If, however, the lamp fails to start the bi-metallic strip 14 will

cool again, thereby closing contacts 12 and 13 to repeat the starting cycle. It will be observed that while contacts 12 and 13 are open and the lamp has not started, substantially full line voltage appears across the high resistor 18. After several starting cycles during which the lamp has failed to start, sufficient heat will be produced by the resistor 18 to maintain the bi-metallic element 14 continuously in a flexed position after the heat from resistor 16 once opens the contacts, thereby continuously keeping contacts 12 and 13 open and preventing reoccurrence of the starting cycle. This condition will persist until the defective lamp is removed from the circuit and a new lamp is substituted or the line switch is opened.

Since the resistor 18 is always across the line while there is a defective lamp in the circuit and the line switch is closed, there will be a continuous current flowing in the circuit. In order to make the energy loss small, it is, therefore, important to make as efficient use as possible of the heat generated by the resistor 18. This aim is achieved by my arrangement of providing direct thermal conduction between the resistor 18 and the thermal element 14.

The use of the direct thermal conduction element 19 has another advantage which makes possible an improved accuracy in the operation of my starter. This consists in making possible the elimination of bends or corrugations in the bi-metallic strip 14 which, it will be noted, is a simple flat strip not formed in any way. By the avoidance of all bending, no stresses are set up in the bi-metallic strip. I have found that as a consequence the amount of deflection of the strip for a given amount of temperature change is substantially constant. Another advantage of making the thermal element 14 in the form of a straight strip of bi-metal is that each strip in routine manufacture will be found to be the same within very close tolerances so that individual calibration of these elements is not required in order to attain the desired accuracy of operation.

In order further to secure accurate operation in spite of ambient temperature changes, I have provided a compensating bi-metallic strip 9 which carries the contact 12 which cooperates with the contact 13 on the main bi-metallic strip 14. The main bi-metallic strip 14 is intended to be deflected only by reason of locally generated heat produced by the resistors 16 and 18. It will, however, in a slight measure deflect in response to ambient temperature changes. While such deflection might not be sufficient to open contacts 12 and 13 even with contact 12 firmly fixed, such ambient temperature deflection tends to produce a variation in the contact pressure which in turn tends to give rise to an inaccuracy in the operation of the starter. My invention avoids this by providing the compensating bi-metallic strip 9, which is, of course, subjected to the same ambient temperature as the main bi-metallic strip 14. Therefore, the contact 12 will be moved in the same direction as the contact 13 is moved by the element 14 in response to ambient temperature changes. It is important in this connection to note the two point anchorage of the compensating bi-metallic strip 9. This anchorage provides the necessary rigidity so that the position of the element 9 will not change with time or due to softening of the supporting member 6 on account of heat which may eventually be developed within the container 1. It is also important to note that the compensating bi-metal is on the opposite

side of the support from the actuating bi-metal and the local heaters. The compensating bi-metal is thus shielded from the heat of the resistors and is only affected by ambient temperature.

What I claim as new and desire to secure by Letters Patent of the United States, is:

- An automatic reset starter for fluorescent lamps comprising a base, an insulating support mounted thereon, first and second terminals mounted on said base and adapted for connection in circuit with the filamentary electrodes of a hot cathode fluorescent lamp, a bi-metallic strip secured by one end on said support, a movable contact on 10 the free end of said strip, a cooperating contact supported from said support, a glow switch connected between said cooperating contact and said first terminal, a low resistance time delay heater for heating said strip to open said contacts after 15 a predetermined period of energization of said element, said low resistance heater being electrically connected to said second terminal and connected to the secured end of said strip by electrically and thermally conductive means, a high 20 resistance lock-out heater for heating said strip to hold said contacts open, said high resistance heater being electrically connected by one lead to said strip between said low resistance heater connection and said movable contact and electrically connected by its other lead to said first 25 terminal, whereby upon the opening of said contacts, said high resistance heater is connected in series with said low resistance heater, said high resistance heater comprising a carbon resistor 30 element having metallic, thermally conductive wire leads in the ends thereof, the said one of which is not substantially longer than the diameter of the element and is fused at its free end directly to said strip for providing a direct heat 35 conductive connection therewith, the electrical connections to the other lead of said element comprising electrical conductors of lower thermal capacity than the thermal capacity of said strip, and said element being mounted on said support 40 45 at an angle to said strip and extending away from said support, whereby heat transfer from said element to said strip is principally through said one lead.
